UNITED STATES PATENT OFFICE.

FREDERICK CHILDS, OF SAN FRANCISCO, CALIFORNIA.

HAND STAMP.

Application filed November 20, 1928. Serial No. 320,740.

My invention relates to hand stamps, in which characters are made to contact with an inking pad so that after being released from contact therewith the characters may 5 be stamped or printed upon a suitable surface, and it concerns particularly an improvement in a self-inking hand stamp, for which a United States Patent, No. 1,547,410, was granted to me on July 28, 1925.

10 In this patent, I disclose a hand stamp of such a construction as to cause the inking pad to swing to the side of the frame structure that holds the character-exposing mechanism therein, by a manual pressure 15 upon a push button in a handle connected with the frame, and to cause the pad automatically to resume its engagement with the exposed characters when the manual pressure upon the push button is released. Al- 20 though the hand stamp disclosed in this patent thus represents a decided forward step in the art, it has certain defects, which, however trivial, still may be objectionable to some of the stamp-using public.

25 One of these defects is that the inking pad engages the exposed characters with a side- 30 also, by the frictional engagement of the 35 pad with the characters, retarding the movement of the pad to its normal, fully registering position relative to the exposed characters when the stamp is not in use. An- 40 other defect is that, because of not having any locking means provided therefor, the inking pad, by careless handling, may be temporarily thrown out of engagement with the exposed characters and made to remain 45 in such a non-engaging position, so that, if an attempt is made to print with the stamp, the exposed characters will not be printed or only partly printed upon the desired sur- 50 face until the pad has been allowed to re- turn to its normal position in which it fully 55 engages the characters.

One object of my present invention is to construct a hand stamp so that the inking pad has a terminal sliding movement to- 50 ward, or an initial sliding movement from, the exposed characters in the stamp, while the remainder of the pad's movement is oscillative, thus entirely avoiding a frictional movement over the characters and thereby 55 prolonging the life of the stamp and causing

the stamp to be quickly and easily operated.

Another object of the invention is to hold the inking pad normally in engagement with the exposed characters and to lock the inking pad in its normal position. 60

A further object in the invention is to provide the stamp with means for stopping the swinging movement of the inking pad when the pad is in the sliding position, thus 65 eliminating unnecessary movements of the inking pad and making the stamp positive in its operation.

Still further objects and advantages will appear from the following detailed description, illustrated in the accompanying draw- 70

ing, in which Figure 1 is a side elevation of a hand stamp constructed in accordance with my present invention, the view showing the inking pad in its normal position, and dotted 75 lines indicating how the stamp is held between the fingers of a person's hand preparatory to the operation thereof;

Figure 2 is an elevation taken from the right of Figure 1 and also showing the inking pad in its normal position, the view being partly in mid-section and partly broken in order to disclose more clearly the in- 80

terior construction; and Figure 3 is an elevation similar to Figure 85 2, but on a reduced scale, and showing the operating handle depressed and the inking pad swung thereby to its extreme lateral position.

The hand stamp of my present invention 90 includes a frame 1, comprising a base mem- 95 ber 2, two forks or lateral members 3 ex- tending virtually right-angularly from the ends of the base member, and an end mem- 100 ber 4, which is virtually right-angularly joined to the ends of the lateral members. In the forks or lateral members 3 is mounted a shaft 5, which preferably extends outside of the members and is reduced at its ends so as to form pivots 6. Upon the shaft 5 with- 105 in the frame 1 is mounted a series of drums 7, each of which is provided with a cus- 110 tomary operating disk 8, and over the re- spective drums and the end member 4 are stretched endless belts 9, upon the outer sur- faces of which are formed printing char- acters 10 adapted to be exposed upon the end member 4 in any desired combination for printing or stamping on a suitable sur- face, the forks preferably tapering toward 110

the end member 4 so as not to extend beyond the outer surfaces of the belts.

The base member 2 is preferably slotted longitudinally as shown at 11, and slots 12 are respectively cut partly into the forks or lateral members 3 so as to form a continuation of the slots 11. A handle 13 is suitably secured to the base member and is provided with a central, flat-bottomed bore 14, which 10 at its bottom and at the end of the handle toward the base member connects with a central bore 15 of a smaller diameter. In the larger bore 14 is loosely fitted a push button 16, to the inner end of which one 15 end of an element in the form of a rod 17, in axial alignment with the push button, is connected, while the other end of the rod is centrally connected with the base member 18 of a yoke 19, which is adapted to embrace 20 the forks 3 of the frame 1 with its branches 20 and to engage the side edges of the slots 12 with the base member so as to allow a sliding and oscillative movement of the yoke, the element 17 and the push button 16. A coil 25 spring 21 around the element 17 in the bore 14 is adapted to force the push button outward and the yoke in the direction of the base member 2 of the frame 1.

An inking pad 22, fitting over the surface 30 of the exposed characters 10, is set into a frame 23, which is provided with arms 24 embracing the forks of the frame 1. Each of the arms 24 has therein a slot 25, which is preferably aligned with the inking pad, and 35 the pivots 6 fit in the respective slots 25 so that the inking pad is thereby pivotally and slidably secured to the frame 1, the shaft 5 and the pivots 6 being preferably aligned with the end member 4 of the frame 1 and thus 40 also aligned with the respective slots 25 when the inking pad is pressed upon the exposed characters 10.

Each of the arms 24 has also at its end another slot 26 in alignment with the slot 25. 45 This slot 26 is formed with side edges 27 and 28, the edge 27 being shorter than the edge 28 and joining a cam portion 29 on the arm. A pin 30 is formed on each of the forks 3 of the frame 1 and is adapted to be 50 in a sliding engagement with the respective side edges 27 and 28, while another pin 31 is formed near the end on each branch 20 of the yoke 19 and each of the arms 24 is perforated so as to slip over and pivotally engage the 55 respective pin 31.

In order to allow a swinging movement of the inking pad 22, the pins 31 are arranged so as to be out of alignment with the pivots 6 and the pins 30, and the branches 20 of the 60 yoke 19 are preferably offset, as shown at 32, and each of the slots 12 has one of its side edges curved, as shown at 33. Thus, during the swinging movement of the inking pad, the curved portions 33 of the slots 12 allow 65 the base member 2 of the frame 1 to respond

to the oscillative impulse as determined by the eccentric relations of the pins 31 to the pivot 6, while the push button 16 by its loose fit in the bore 14 is free to follow the oscillative movement, as is also the element 70 17, which may have a portion 34 of its side cut out in order to clear the edges of the bore 14.

When it is desired to use the stamp, the operator preferably grips the handle 13 75 thereof with two fingers of one hand, while with the thumb he depresses the push button 16, as indicated by dotted lines in Figure 1. The initial movement of the inking pad will be a direct sliding away from the exposed characters with which it is normally in contact.

When during this sliding movement the arms 24 of the pad frame 23 reach a position wherein the pins 30 contact the respective 85 cam portions 29, the arms are thereby assisted in beginning their combined swinging and sliding movement on the pivots 6. The push button may be depressed until the base member 18 reaches the end of the slots 12, 90 which thus stop a further movement of the inking pad and at the same time prevent the base member 18 from hitting the operating disks 8 of the drums 7.

When the inking pad has been swung to this position, as shown in Figure 3, the operator may retain his finger grip on the handle while he is printing the exposed characters on the desired surface. As he releases his pressure on the push button, the spring 21 100 automatically forces the push button outward and causes the inking pad to swing back to its position in alignment with the exposed characters. The inking pad is stopped in this aligned position by the contact of the 105 long edges 28 of the slots 25 with the respective pins 30, and, as the spring 21 continues to urge the push button outward, the pins 30 enter fully into the slots 26 and engage the respective side edges of the slots, thereby 110 locking the inking pad in the position in which it is thus normally held in contact with the exposed characters, so that in the manner described, the stamp is always ready 115 for a repeated use.

It should be observed that, although for the sake of convenience I have shown the pivots 6 as being at the ends of the shaft 5 on which the drums 7 are mounted, such pivots may be arranged in other convenient places on the 120 frame 1, and the arrangement of the other parts of the stamp may be correspondingly modified in order that the operation of the stamp may be effected in a manner similar to that already described.

It is also evident that, as the inking pad eventually wears, the wear is automatically taken up by the pad's sliding movement toward the exposed characters. The base member 18 of the yoke 19 is for this reason allowed 130

to slide freely within the slot 11 and toward the handle 13, as is understood from the disclosure in Figure 2.

I claim as my invention:

5. 1. In a hand stamp, a frame adapted to have characters mounted therein and exposed at one end thereof; a handle secured to the frame at its other end; an inking pad pivotally and slidably secured to the frame so as to be adapted to be slid toward or away from the exposed characters and to be swung from its sliding position to one side of the frame or from the sidewise position to the sliding position; means slidably and oscillatively extending through the handle and pivotally connected with the inking pad for sliding and swinging the pad; and means for normally holding the inking pad in the sliding position and pressed upon the exposed characters.

10 2. In a hand stamp, a frame adapted to have characters mounted therein and exposed at one end thereof; a handle secured to the frame at its other end; an inking pad pivotally and slidably secured to the frame so as to be adapted to be slid toward or away from the exposed characters and to be swung from its sliding position to one side of the frame or from the sidewise position to the sliding position; means slidably and oscillatively extending through the handle and pivotally connected with the inking pad for sliding and swinging the pad; means for normally holding the inking pad in the sliding position and pressed upon the exposed characters; and means for locking the inking pad in its normal position.

15 3. In a hand stamp, a frame adapted to have characters mounted therein and exposed at one end thereof; a handle secured to the frame at its other end; an inking pad pivotally and slidably secured to the frame so as to be adapted to be slid toward or away from the exposed characters and to be swung from its sliding position to one side of the frame or from the sidewise position to the sliding position; means slidably and oscillatively extending through the handle and pivotally connected with the inking pad for sliding and swinging the pad; means for stopping the swinging movement of the inking pad when the pad is in the sliding position; and means for normally holding the inking pad in the sliding position and pressed upon the exposed characters.

20 4. In a hand stamp, a frame adapted to have characters mounted therein and exposed at one end thereof; a handle secured to the frame at its other end; an inking pad pivotally and slidably secured to the frame so as to be adapted to be slid toward or away from the exposed characters and to be swung from its sliding position to one side of the frame or from the sidewise position to the sliding position; means slidably and oscillatively extending through the handle and pivotally connected with the inking pad for sliding and swinging the pad; and means for normally holding the inking pad in the sliding position and pressed upon the exposed characters.

25 5. A hand stamp comprising a forked frame adapted to have characters mounted therein and exposed at one end thereof; a handle secured to the frame at its other end; an inking pad provided with arms that embrace the forks of the frame and pivotally and slidably engage respective pivots extending outward from the forks of the frame, the inking pads being adapted to be slid toward or away from the exposed characters and to be swung from its sliding position to one side of the frame or from the sidewise position to the sliding position; a yoke embracing the forks of the frame and being pivotally connected with the arms of the inking pad, the yoke having connected therewith an element slidably and oscillatively extending through the handle so that the inking pad may be slid and swung by the movement of the yoke; and means for actuating the yoke so as to normally hold the inking pad in the sliding position and pressed upon the exposed characters.

30 6. A hand stamp comprising a forked frame adapted to have characters mounted therein and exposed at one end thereof; a handle secured to the frame at its other end; an inking pad provided with arms that embrace the forks of the frame and pivotally and slidably engage respective pivots extending outward from the forks of the frame, the inking pad thus being adapted to be slid toward or away from the exposed characters and to be swung from its sliding position to one side of the frame or from the sidewise position to the sliding position; a yoke embracing the forks of the frame and being pivotally connected with the arms of the inking pad, the yoke having connected therewith an element slidably and oscillatively extending through the handle so that the inking pad may be slid and swung by the movement of the yoke; means for actuating the yoke so as to normally hold the inking pad in the sliding position and pressed upon the exposed characters; and pins upon the forks of the frame adapted to engage the side edges of slots formed respectively in the ends of the arms so as to lock the inking pad in its normal position.

35 7. A hand stamp comprising a forked frame adapted to have characters mounted therein and exposed at one end thereof; a handle secured to the frame at its other end; an inking pad provided with arms that embrace the forks of the frame and pivotally and slidably engage respective pivots extend-

ing outward from the forks of the frame, the inking pad thus being adapted to be slid toward or away from the exposed characters and to be swung from its sliding position to one side of the frame or from the sidewise position to the sliding position; a yoke embracing the forks of the frame and being pivotally connected with the arms of the inking pad, the yoke having connected therewith an element slidably and oscillatively extending through the handle so that the inking pad may be slid and swung by the movement of the yoke; means for actuating the yoke so as

to normally hold the inking pad in the sliding position and pressed upon the exposed characters; and pins upon the forks of the frame adapted to engage the side edges of slots formed respectively in the ends of the arms so as to lock the inking pad in its normal position, one of the side edges of the respective slots being longer than the other side edge so as to strike the respective pin and thereby stop the swinging movement of the pad when the pad reaches its sliding position. 15 20
